United States Patent Office

Des. 187,936
Patented May 17, 1960

187,936

CLOCK OR SIMILAR ARTICLE

William V. Judson, Westport, Conn., assignor to General
Electric Company, a corporation of New York

Application December 7, 1959, Serial No. 58,579

Term of patent 7 years

(Cl. D42—7)

Des. 187,936

PAGE 2

Fig. 3.

Fig. 1 is a front perspective view of a clock embodying my new design;

Fig. 2 is a front elevational view of the clock shown in Fig. 1; and

Fig. 3 is a side elevational view of the clock shown in Fig. 1.

I claim:

The ornamental design for a clock or similar article, substantially as shown.
